(57) **CLAIM**

The ornamental design for an oval dining table, as shown and described.

DESCRIPTION

FIG. 1 is a perspective view showing the new design; FIG. 2 is an end view thereof, the opposite end view being a mirror image thereof;

FIG. 3 is a side view thereof, the opposite side view being a mirror image thereof; and,

FIG. 4 is a bottom view thereof.

The broken lines are for environmental purposes only and form no part of the claimed design.
